INVENTOR:
Henry B. Cooley,
BY
Arthur B. Jenkins,
ATTORNEY.

UNITED STATES PATENT OFFICE.

HENRY B. COOLEY, OF KENSINGTON, CONNECTICUT, ASSIGNOR TO THE AMERICAN PAPER GOODS COMPANY, OF KENSINGTON, CONNECTICUT, A CORPORATION OF CONNECTICUT.

SANITARY DISPENSING APPARATUS.

Application filed May 21, 1923. Serial No. 640,845.

To all whom it may concern:

Be it known that I, HENRY B. COOLEY, a citizen of the United States, and a resident of Kensington, in the county of Hartford and State of Connecticut, have invented a certain new and useful Improvement in Sanitary Dispensing Apparatus, of which the following is a specification.

My invention relates to the class of apparatus employed for dispensing various articles, and an object of my invention, among others, is to provide an apparatus of this class that is especially simple in construction and particularly efficient in operation; and a further object of the invention is to provide an apparatus of this class that shall be extremely sanitary.

One form of apparatus embodying my invention, and in the construction and use of which the objects herein set out, as well as others, may be attained, is illustrated in the accompanying drawings, in which—

Figure 1 is a side view of my improved dispensing apparatus.

Figure 2 is a similar view with the lower part of the magazine broken away and showing the detents at the instant of preliminary engagement with the stack of cups in the magazine.

Figure 3 is a view similar to Figure 2, but showing the position of the detents just after disengagement of the lower cup in the stack from the retainer in the magazine.

Figure 4 is a view in cross section on a plane denoted by the dotted lines 4—4 in Fig. 1.

My invention is not limited in its use to an apparatus for dispensing articles, as it may be readily employed in vending machines. Neither is it limited in its use to an apparatus for dispensing or vending any specific class of articles, but as it is readily adapted for use in an apparatus for dispensing drinking cups, I have selected such an apparatus for the purpose of illustrating and describing my invention herein.

Such apparatus comprises in its structure a case or magazine 6 and a support 7, said support and magazine being arranged for relative movement one with respect to the other. In the special form of apparatus herein disclosed the support 7 is in the form of a post secured to and rising from a base 8 that may be provided with a clamp 9 of any suitable construction for securing the

apparatus to a fixed object, as a shelf. A bracket 10 is secured to the upper end of the post and the case or magazine 6 is pivotally attached, preferably at its upper part, to said bracket. This magazine has a retainer or retainers 11 projecting from the surface of its inner wall and an opening 12 through said wall. The retainer or retainers are preferably located on one side of the magazine only and adjacent to said opening.

A retaining detent 13 and a disengaging detent 14 are supported for relative movement with respect to the case and also with respect to each other. In a particularly satisfactory device these retainers are, either or both, supported for swinging movement in such manner that the disengaging detent will have a disengaging movement with respect to the retaining detent, the term "disengaging" being employed herein to denote that movement for disengaging articles, as cups, from a stack or pile of articles or cups.

In the particular form of apparatus illustrated and described herein, these detents are each supported by a spring and each detent is preferably in the form of a lip at the end of each spring. In this form of the apparatus the retaining detent 13 is located on the case or magazine 6 and the disengaging detent 14 is secured to and projects from the support 7. A spring 15 supporting the retaining detent is bent outwardly away from the magazine and a spring 16 supporting the disengaging detent is curved toward the magazine so that the two detents, when in their normal positions, will be close together or in contact one with the other.

In operation a stack or pile of cups 17 is located in the magazine with a bead or lip 18 at the mouth of the bottom cup resting upon the retainers 11, the detents being spaced from the stack or pile of cups, as shown in Figure 1 of the drawings. The magazine being now swung toward the post or support 7 both of the detents will be caused to make contact with the stack of cups, engaging such stack between the bead or lip on the bottom cup in the stack and the bead or lip on the next cup thereto. A continued swinging movement of the magazine, and consequent swinging movement of the detents, will cause the disengaging detent to move away from the retaining detent,

and, being in engagement with the top edge of the bottom cup in the stack, the latter will be forced away from the stack and will drop through the opening in the bottom of the magazine, the retaining detent, in connection with the retainers 11 preventing downward movement of the balance of the cups in the stack. Upon a return movement of the magazine to its normal position the 10 detents will assume their normal position as illustrated in Figure 1 and the operation may be repeated.

As a means for returning the magazine to its normal position, I have provided a magazine returning spring 19 attached at its opposite ends to the upper end of the magazine and to the support 7, but this returning spring is not absolutely essential in all cases, as the springs bearing the detents may be 20 employed to effect the operation of the magazine, but I prefer to employ the returning spring.

In order to provide for a sanitary use of this apparatus I form a magazine operating 25 lip 20 on one side of the opening at the lower end of the magazine, against which lip a container 21, in the form of a cup if desired, may be pressed to move the magazine toward its support, this container being 30 placed upon the upper surface of the clamp 9 and pushed along such surface that serves as a table 22. In this operation the lower cup when it is disengaged from the stack will drop into said container, which, when 35 removed from underneath the stack, will present the cup in readiness to receive a liquid, as a beverage, this without removing the cup from the container, and the beverage may be drunk without removing the cup 40 from the container.

This apparatus is of particular value in dispensing beverages from soda fountains and the like, as the cups do not have to be handled by the person dispensing the beverage or by the person partaking of the beverage, and extremely sanitary conditions 45 thus prevail.

It is not essential to my invention that the magazine shall be movably mounted to 50 provide the relative movement between it and the detents, nor that the relative movement between the detents shall be obtained as herein set forth, nor that the detents shall be supported on the parts as herein illustrated, as other arrangements to secure the desired results may be made use of, and the invention is not therefore limited in its application to the construction herein disclosed, although I prefer to arrange the 55 mechanism as hereinbefore specifically set out.

As a means for supplementing the action of the disengaging detent I may provide a supplemental spring 23 secured to the support 7 and arranged to press against the 60

back of the spring 16 to aid the latter in its action.

In accordance with the provisions of the patent statutes I have described the principles of operation of my invention, together 70 with the device which I now consider to represent the best embodiment thereof, but I desire to have it understood that the device shown is only illustrative and that the invention may be carried out by other means 75 and applied to uses other than those above set out.

I claim—

1. A dispensing apparatus comprising a base, a magazine member and a detent member supported in cooperative relation by said base, each of which is independently movably mounted and in constant operative engagement, means for supporting a stack of articles in said magazine, means for moving one of said members toward the other, means influenced by said movement to effect relative movement between the magazine and detent instantly at the beginning of such movement and longitudinally of the 80 magazine to positively disengage an article from within said magazine, and means for thereafter starting and completing a return movement of the parts to their normal position. 95

2. A dispensing apparatus comprising a base, a magazine member and a detent member supported in cooperative relation by said base and swingingly mounted one independently of the other and in constant operative engagement, means for supporting a stack of articles in said magazine, means for swingingly moving one of said members toward the other, means influenced by said swinging movement to effect relative movement between the magazine and detent instantly at the beginning of the swinging movement and longitudinally of the magazine to positively disengage an article from within the magazine, and means for thereafter starting and completing return movement of the parts to their normal positions. 100

3. A dispensing apparatus comprising a base, a magazine and a detent with the magazine and detent mounted to move in curved paths from different centers supported in cooperative relation by said base with the magazine and detent swinging movements in one direction of the magazine and detent imparting relative movement between the detent and magazine longitudinally of the latter, and means within the magazine for supporting articles in the path of movement of said detent. 115

4. A dispensing apparatus comprising a base, a magazine supported by said base, a detent fixed at one end in spaced cooperative relation with respect to the magazine and with its opposite end movable in a curved path and in constant engagement with the 120 125 130

magazine, means for supporting articles in the magazine, and means for imparting relative movement between the magazine and fixed part of the detent to thereby cause relative movement between the detent and magazine longitudinally of the latter to disengage articles from within the magazine.

5. A dispensing apparatus comprising a base, a magazine supported by said base, a 10 detent pivotally mounted on a fixed support on said base in cooperative relation with respect to said magazine and with its end to move in a circular path and contacting the magazine, means for supporting a stack 15 of articles in the magazine, and means for imparting relative movement between said support and magazine to cause swinging movement of the detent and thereby movement of the detent longitudinally of the 20 magazine to disengage articles therefrom.

6. A dispensing apparatus comprising a base, a magazine supported by said base and pivotally mounted at one end, a detent supported by said base and located near the 25 swinging end of the magazine in cooperative relation with respect thereto with one end engaging the magazine and movable in a curved path different from that of the magazine to cause movement of the detent longitudinally of the magazine when the maga-

zine and detent are moved, and means for supporting articles within the magazine.

7. A dispensing apparatus comprising a base, a magazine pivotally mounted at one end and supported by said base, a detent 35 supported by said base located near the swinging end of the magazine in cooperative relation with respect thereto and comprising a spring arm fixed at one end and with its opposite end engaging the magazine and 40 moving in a curved path different from that of the magazine to cause movement of the detent longitudinally of the magazine when the magazine and detent are moved, and means for supporting articles in the magazine. 45

8. A dispensing apparatus comprising a support, a magazine pivotally mounted adjacent one end of the support, a detent mounted on the support with its free operative end engaging the magazine, the mounting for the magazine and detent being at different points to cause the free moving ends thereof to move through different curved paths with the operative end of the 50 detent moving longitudinally of the magazine for the ejection of an article and remaining engaged with the magazine. 55

HENRY B. COOLEY.
